UNITED STATES PATENT OFFICE.

GEORGE W. FOUBE, OF SACRAMENTO, CALIFORNIA, ASSIGNOR, BY MESNE ASSIGNMENTS, TO NATIONAL MANUFACTURING COMPANY, OF SAN FRANCISCO, CALIFORNIA, A CORPORATION OF CALIFORNIA.

ROTARY VALVE FOR INTERNAL-COMBUSTION ENGINES.

1,172,782.

Specification of Letters Patent. Patented Feb. 22, 1916.

Application filed April 25, 1912, Serial No. 693,074. Renewed July 21, 1915. Serial No. 41,188.

To all whom it may concern:

Be it known that I, GEORGE W. FOUBE, citizen of the United States, residing at Sacramento, in the county of Sacramento and State of California, have invented new and useful Improvements in Rotary Valves for Internal-Combustion Engines, of which the following is a specification.

This invention relates to rotary valves for internal combustion engines.

It is the object of this invention to provide a rotary valve for controlling the delivery and discharge of gases to and from engine cylinders, and which is designed to obviate the use of cams, push rods, puppet valves, springs, and the like.

A further object is to provide a rotary valve for internal combustion engines by means of which the explosive mixture delivered to the engine cylinders will be superheated from the heat generated by the exhaust gases.

A further object is to provide a rotary valve of the above character which is simple in construction and efficient in operation, and which is adapted to be adjusted to compensate for wear of the valve surface.

The invention consists of the parts and the combination and construction of parts as hereinafter more fully described and claimed, having reference to the accompanying drawings, in which—

Figure 1 is a view in vertical section of a gas engine showing the invention as applied. Fig. 2 is a detail longitudinal section of the rotary valve. Fig. 3 is an enlarged section on the line X—X of Fig. 2. Fig. 4 is an enlarged section on the line Y—Y of Fig. 2.

In the drawings, A, B, C and D represent a series of engine cylinders in which pistons 2 are reciprocably mounted in the usual manner; the pistons 2 being connected to a crank shaft 3 by means of piston rods in the usual manner. The upper ends of each of the engine cylinders A, B, C and D are formed with inlet and exhaust ports 4 and 5, respectively, which ports open into the interior of a valve casing 6, extending in a horizontal direction above the engine cylinders A, B, C and D, as shown in Fig. 1. The ports 4 and 5 in the cylinders A, B, C and D are arranged in alinement on the longitudinal center of the valve casing 6, and are spaced a suitable distance apart. Mounted

in the valve casing 6 is a tapered tubular valve 7, which is designed to rotate in the valve casing 6, as will be later described, to alternately open and close the ports 4 and 5. The valve casing 6 is constructed to conform to the tapered surface of the valve 7; the outer surface of the valve 7 slidably contacting the inner surface of the valve casing 6 so as to form a sufficiently tight joint between the ports 4 and 5 as to prevent the passage of the gases from one port to another. Means are provided for adjusting the valve 7 in the valve casing 6 so as to compensate for wear on its outer surface and to adjust its contact with the inner surface of the valve casing, which means is here shown as consisting of a set-screw 8, mounted to bear against the outer end of a shaft 9 carried on one end by the valve 7, and a crowding ring 10 arranged to bear against the other end of the valve 7.

The crowding ring 10 is threaded on its outer periphery and is adapted to be screwed into a cap 11 which closes the large end of the valve casing 6; the cap 11 being secured to the valve casing 6 by means of bolts 11', or in any other suitable manner. Formed on the outer end of the valve 7 is a conical trunnion 12 which extends into and is surrounded by the crowding ring 10, the inner face of which conforms to the outer face of the trunnion 12. In adjusting the valve 7 longitudinally in the valve casing 6, the crowding ring 10 is turned in its threaded bearing in the cap 11 so as to bear against the conical face of the trunnion 12, and thereby crowd the valve 7 lengthwise into the valve casing 6 until the required degree of contact between the valve 7 and the valve casing 6 is obtained.

The set-screw 8 is mounted on a frame 13 carried by the valve casing 6 and extends in a horizontal direction so that its inner end will bear against the outer end of the shaft 9 which is formed on the longitudinal axis of the valve 7; the set-screw 8 forming an adjustable abutment for limiting the longitudinal movement of the valve 7 when the latter is crowded lengthwise into the valve casing 6 by means of the crowding ring 10.

Mounted on the shaft 9 is a beveled gear 14 which meshes with a similar gear on a vertically disposed shaft 16, which is designed to be rotated from the crank

shaft 3 through a series of gears indicated at 17 in such manner as to rotate the gear 14 and thereby rotate the valve 7 through the shaft 9. The mounting of the beveled gear on the shaft, 9, may be effected by splining or such other well known means as will permit the shaft to slide relatively to the gear when adjusting the valve in the manner stated. Mounted within the valve 7 and extending longitudinally therein is a tube 18, the outer periphery of which is spaced from the inner periphery of the valve 7, forming an annular chamber between the walls of the valve 7 and the walls of the tube 18. The inner end of the tube 18 terminates a short distance from the inner end of the valve 17 while its outer end passes through the trunnion 12 on the outer end of the valve 7 and connects with a feed pipe 19 leading from any suitable source of supply, and which is attached to the cap 11, as shown in Fig. 1, and through which explosive gases are designed to be delivered continuously to the interior of the valve 7. Formed in the walls of the valve 7 are a series of diametrically opposed perforations 29, which are designed to register with the inlet ports 4 of the engine cylinder, when the valve 7 is rotated; the perforations 20 forming a means of communication between the interior of the valve 7 and the interior of the engine cylinders through the ports 4. A series of oppositely disposed perforations 21 are formed in the walls of the valve 7 in such position as to register with the ports 5 when the valve 7 is rotated. The opposed perforations 21 open to tubes 22, which are diametrically arranged within the valve 7 and extend through tube 18, as particularly shown in Fig. 3. The tubes 22 form passages leading through the valve 7 in alignment with the exhaust ports 5 so as to provide communications between the interior of the engine cylinders and the atmosphere, through the ports 5 and ports 22, formed in the valve casing 6, which open to an exhaust pipe 23, as shown in Fig. 1.

In the operation of the invention the explosive mixture is delivered to the interior of the valve 7 through the conduit 19, and the tube 18; the valve 7 is rotated from the crank shaft 3 through the gears 17, shaft 16, gears 15-14, and the shaft 9, at a ratio of one-fourth of a revolution of the valve 7 to one revolution of the crank 3. When the perforations 20, in the valve 7 register with the ports 4 in the engine cylinders, the explosive mixture will be drawn into the engine cylinders on the down stroke of the pistons; the area of the perforations 20 and their positions in relation to each other being such as to open the ports 4 to form a communication between the interior of the engine cylinders and the valve 7 on the suction or intake strokes of the pistons 2; the

ports 4 being closed by the walls of the valve 7 during the compression, explosion or scavenging strokes of the pistons 2.

The perforations 21 are of such area and are disposed in such relation to each other and to the ports 5 as to open the latter on the exhaust or scavenging strokes of the pistons 2; the walls of the valve 7 closing the ports 5 during the intake compression and explosion strokes of the pistons 2. When the ports 5 are opening to the perforations 21, the hot exhaust gases will pass through the tubes 22 and be discharged to the atmosphere through the pipe 23; the hot gases passing through the tubes 22, heating the latter in such manner as to superheat the explosive mixture in the valve 7 previous to its being delivered to the engine cylinders; the explosive mixture on passing through the tube 18 circulating around the tubes 22 passing transversely therethrough.

By discharging the explosive mixture into the valve 7 adjacent its inner end it will be caused to flow back through the interior of the valve 7 in order to enter the engine cylinders arranged near the outer end of the valve, so as to insure an effective distribution of the superheated explosive mixture of the several cylinders.

It is obvious that while I have shown four engine cylinders A-B-C-D in this case, that any desired number of engine cylinders may be connected and controlled by a single valve 7.

Having thus described my invention, what I claim and desire to secure by Letters Patent is—

1. In an internal combustion engine, the combination with a series of engine cylinders of a horizontally disposed valve casing formed with inlet and exhaust ports opening to the engine cylinders, a rotary tubular valve in said casing having diametrically spaced ports therein arranged to register with the inlet ports, and having diametrically disposed passages leading therethrough registerable with the exhaust ports, and a tube extending longitudinally into the valve to a point near the inner end thereof for introducing an explosive mixture into the interior of the tubular valve.

2. In an internal combustion engine, the combination with a series of engine cylinders of a horizontally disposed valve casing formed with inlet and exhaust ports opening to the engine cylinders, a rotary tubular valve in said casing having diametrically spaced ports therein arranged to register with the inlet ports, and having diametrically disposed passages leading therethrough registerable with the exhaust ports, and means for introducing an explosive mixture into the interior of the tubular valve, including a tube extending longitudinally into the valve and opening adjacent the in-

- ner end thereof, and a conduit leading to said tube.
3. In an internal combustion engine, the combination with a series of engine cylinders of a horizontally disposed valve casing formed with inlet and exhaust ports opening to the engine cylinders, a rotary tubular valve in said casing having diametrically spaced ports therein arranged to register with the inlet ports, and having diametrically disposed passages leading therethrough registerable with the exhaust ports, and means for introducing an explosive mixture into the interior of the tubular valve, including a tube extending longitudinally into the valve and opening adjacent the inner end thereof, and a conduit leading to said tube, said exhaust passages passing through the tube and separated therefrom by cylindrical walls.
4. In an internal combustion engine, the combination with a series of engine cylinders of a horizontally disposed valve casing formed with inlet and exhaust ports opening to the engine cylinders, a rotary tubular valve in said casing having diametrically spaced ports therein arranged to register with the inlet ports, and having diametrically disposed passages leading therethrough registerable with the exhaust ports, means for introducing an explosive mixture into the interior of the tubular valve, including a tube extending longitudinally into the valve and opening adjacent the inner
- end thereof, and a conduit leading to said tube, said exhaust passages passing through the tube and separated therefrom by cylindrical walls, and means for adjusting the tubular valve lengthwise in its casing.
5. In combination with a multiple cylinder combustion engine having inlet and exhaust ports for each cylinder, a hollow cylindrical rotary valve having inlet ports through its wall and communicating with its interior and adapted to register with the cylinder inlet ports, interior webs extending across the hollow valve and forming exhaust ports entirely within the valve and extending completely therethrough, there being an exhaust port situated oppositely to each of the cylinder exhaust ports with which port the valve exhaust ports register when they register with the cylinder exhaust ports.
6. In a device of the character described, a revoluble hollow cylindrical valve having inlet ports through its peripheral wall, webs extending interiorly across the hollow valve and forming exhaust ports extending through the valve from outer face to outer face thereof.
- In testimony whereof I have hereunto set my hand in the presence of two subscribing witnesses.
